UNITED STATES PATENT OFFICE.

EDWIN J. MURPHY, OF SCHENECTADY, NEW YORK, ASSIGNOR TO GENERAL ELECTRIC COMPANY, A CORPORATION OF NEW YORK.

ELECTROMAGNETIC SWITCH.

1,306,555.

Specification of Letters Patent. Patented June 10, 1919.

Application filed April 29, 1916. Serial No. 94,465.

To all whom it may concern:

Be it known that I, EDWIN J. MURPHY, a citizen of the United States, residing at Schenectady, county of Schenectady, State 5 of New York, have invented certain new and useful Improvements in Electromagnetic Switches, of which the following is a specification.

My invention relates to means for controlling the circuits of electric motors and more particularly to improved means whereby an electric motor may be started and automatically brought up to running speed.

In the starting of electric motors, it has 15 been the practice to employ a plurality of electromagnetic switches which close successively to cut out sections of resistance from the motor circuit and bring the motor up to speed. Various means have been devised 20 for controlling the operation of the switches so that they will only close when the current is at a proper value, that is, after a switch has operated to cut out a section of resistance the next switch will not operate until the current has dropped to a safe 25 value due to the speeding up of the motor.

A form of switch which has frequently been proposed for this purpose is one in which a shunt coil closes the switch and a 30 series coil, instead of controlling the circuit of the shunt coil, positively prevents the switch from closing by actually holding it open, that is, the shunt coil pulls against the series or "holding out" coil. A switch 35 of this general character is disclosed in patent to Fraser #655,335. The difficulty with the device shown in this patent is that the value of current in the holding out winding at which the switch will close depends 40 upon the pull of the shunt coil, which of course will vary with the voltage and also with the temperature of the coil. In other words, the "setting" of the switch, i. e. the motor current value at which it closes, 45 changes with change of voltage. It also closes at one value of current in the series coil when the shunt coil is cold and another when it is at its operating temperature, which is ordinarily about 60 degrees C.

Attempts have been made to overcome 50 this difficulty by having an auxiliary member, which is operated by the shunt coil, place a spring under tension which tends to move the switch member to closed position. This tendency is opposed by the series

coil when the current is high and when the current drops to a predetermined value, the spring overcomes the pull of the series coil and closes the switch. Such an arrangement is unsatisfactory for the reason that 60 the switch is closed by a spring instead of by electromagnetic pull, and it is impossible to obtain the required pressure between the contacts. The spring weakens as the switch member moves toward closed position, and 65 the pressing together of the contacts is accomplished when the spring is weakest. As the parts wear, the pressure between the contacts decreases.

One of the objects of my invention is to 70 improve the electromagnetic switch of the type above described by providing means whereby the switch member will be operated so as to be positively closed and wiped home by the electromagnetic pull of the 75 shunt coil when the current in the series coil drops to a predetermined value, the arrangement being such that the value of current in the series coil at which the switch closes will be independent of the variations in pull 80 of the shunt coil due to variations in voltage and other causes.

In the accompanying drawing illustrating 85 my invention embodied in concrete form, Figure 1 is a side elevation of an electromagnetic switch embodying my invention; Fig. 2 is a front elevation of the same; Figs. 3 and 4 are diagrammatic views of the switch 90 showing the parts in different positions; Fig. 5 is a diagrammatic view showing my switches connected to start a motor, and Figs. 6-10 are similar views of a modified form of my invention.

Referring to the drawing, 10 represents the slate base upon which the parts are 95 mounted. These parts comprise, a stationary contact 11, a switch member 12 operated by a shunt coil 13 to move the switch member into engagement with the stationary contact, and a series holding out coil 14 which 100 permits the switch member 12 to close only when its energizing current is below a predetermined value. The magnetic structure for the shunt coil 13 is in the form of a U shaped magnet frame 15 having a pole piece 105 16 co-operating with the switch member and a leg 17 to which the switch member is pivoted at 18. The switch member is provided with the usual contact 19 supported by spring 20 so that the contacts 11 and 19 110

may wipe upon each other as the spring 20 yields in a well understood manner.

- In order to prevent the switch member from closing when the current in the series coil 14 is above a predetermined value I provide means whereby the series coil is opposed by a spring instead of by the shunt coil, although it is not this spring but the shunt coil which closes the switch.
- 10 In the particular arrangement shown in the drawing, I provide a locking member 21 pivoted at 22 so that when the current in the winding 14 is above a predetermined value (or for that matter, even when the 15 windings are deenergized), it will prevent the closing of the switch member. As shown a stop finger 23 engages the locking member 21 to prevent the closing movement of the switch member 12 when the locking member 20 is in the position shown in the drawing. This locking member 21 is controlled by a member 24 pivoted at 25 which acts as an armature for the winding 14. This 25 armature member is provided with a projection 26 which engages the locking member 21. The switch member 12 and the armature member 24 are connected by a resilient connection such that when the switch member starts to move, it compresses 30 the spring 27 which tends to force the armature member 24 away from the magnet and trip the locking member. The armature member is normally in the position shown in the drawing, that is, it rests against the 35 pole piece of the magnet 14, it being held in this position by the weight of the switch member acting through the rod 28 extending through the spring 27 having nuts 29 at its lower end as shown which bear against 40 the lug 30 on the armature member. The latch 21 is held in the position shown in Figs. 1 and 3 of the drawing by the pin 31. As thus constructed and arranged, the 45 operation of my device will be as follows:
- Normally the parts will be in the position shown in Fig. 1 of the drawing. Assuming that the two windings of the switch are energized simultaneously and the winding 14 energized by a current above the value at 50 which it is desired that the switch should close, the parts will assume the position shown in Fig. 3. Referring to this figure it will be seen that the switch member 12 has been moved slightly until the stop finger 55 23 engages the locking member 21. This causes a certain amount of compression of the spring 27 tending to move the armature member 24 on its pivot but this tendency is resisted by the magnet winding 14. The 60 shunt coil is now pulling the switch member against the locking member or latch and the switch member can not close until the latch is tripped. It will also be observed that the tripping of the latch, and therefore 65 the release of the switch member depends

entirely upon the current in the winding 14. The magnet winding 14 is acting against a constant force, viz. the tension of the spring 27 so that when the current drops to a predetermined value, the armature member will 70 be released and deliver a hammer blow to the latch 21. The parts will now assume the position shown in Fig. 4 in which it will be seen that the latch has been tripped and the switch member is positively closed and 75 the contacts wiped home by the shunt coil. The switch member is therefore positively held open under the control of the current in the series coil and the variations of pull in the shunt coil will have no effect whatever upon the value of current at which the switch member will close.

In Fig. 5, I have shown a diagram of connections for starting an electric motor in which a plurality of switches of the type 80 above described are used as resistance switches. Referring to this figure, A represents the armature and F the shunt field of an electric motor. B is an electrically operated line switch for closing the armature circuit and is provided with interlocking contacts C which connect the shunt coils 13 of the various resistance switches D, E and F in circuit. In order to effect automatic progression of these switches, I divide the series coils 14 of all but the first one to operate into two parts. The arrangement is such that when the first switch F closes, a portion of the series winding of the next switch is cut out to reduce the number of ampere turns so as to enable the switch to close when the current drops to a predetermined value. Likewise when the second switch closes, it cuts out a portion of the series winding of the next switch.

The operation of this system will now be understood from an inspection of Fig. 5. When the line switch B closes, the armature circuit is completed from the positive side of the line through starting resistances R, R', R² and through the series windings 14 to the negative side of the line. The interlocking contact C on the line switch places all of the shunt coils 14 in circuit across the line. When the current drops to the proper value, the first switch F will close thereby short-circuiting resistance R², its own series coil 14, and a portion of the series winding 14 of switch E. When the current again drops to a proper value, due to the speeding up of the motor, the switch E will close, short-circuiting resistance R', its own series winding, and a portion of the series winding of switch D. When the current again drops to the proper value, the switch D will close, thereby connecting the motor directly across the line.

Referring to Figs. 6 to 10, it will be seen that I have shown a modified arrangement for holding the switch member in open posi-

tion. In this case the series coil 14 is provided with an armature 32 pivoted at 33. This armature is connected with the switch arm 34 by a U-shaped member 35, there 5 being an extension 36 on the switch arm 34 for making connection. The link is pivoted to the armature at 37 by a slotted connection so that the link may be moved longitudinally to the right with reference to the armature. This movement of the link, which as 10 shown is slight, compresses a spring 38 surrounding a rod 39, one end of which bears against the link. The rod 39 slides in a projection on the armature 32 and at right angles thereto. The spring 38 is interposed between a shoulder 41 on the rod and the projection 40. When the parts are in their normal positions, the pivot points 33 and 37 are in line with pivot point 42 connecting 15 the link with the switch arm extension 36. When a force is applied to the switch arm, therefore tending to move it to closed position, there is no tendency for the armature to move away from the magnet due to the 20 pull of the shunt coil. There is a small initial movement however of the link by reason of the sliding connection with the armature which compresses the spring 38. The reaction of the spring 38 against the projection 25 40 tends to force the armature 32 away from its magnet. When the current in the winding 14 drops to a predetermined value, the spring will overcome the magnetic pull. The armature will turn on its pivot and 30 throw the pivot points out of line so that the shunt coil will close the switch, the parts assuming the position shown in Fig. 10. This form of switch may be used in the system shown in Fig. 5.

40 It will be seen that I have provided an electromagnetic switch which is closed by a shunt coil but is held open while the current in the series coil is above the predetermined value, the closing point of the switch always 45 being the same regardless of the variations in pull of the shunt coil.

While I have described my invention as embodying a concrete structure and as operating in a specific manner in accordance 50 with the provisions of the patent statutes, it should be understood that I do not limit my invention thereto, since various modifications thereof will suggest themselves to those skilled in the art without departing 55 from the spirit of my invention, the scope of which is set forth in the annexed claims.

What I claim as new and desire to secure by Letters Patent of the United States, is:—

1. An electromagnetic switch comprising 60 a switch member, an actuating winding connected to a source of substantially constant potential, and a magnetic structure, therefor for moving the switch member to closed position, a winding carrying a variable current and means whereby the switch member

is held in open position when the current in the latter winding is above a predetermined value and is closed by the potential coil when the current drops to said value regardless of variations in the pull of the 70 potential coil.

2. An electromagnetic switch comprising a switch member, a shunt coil for closing the same, a winding carrying a variable current, means for preventing the closure of the 75 switch member when the current in said winding is high and means for releasing the switch member to permit it to be closed by the shunt coil when the current in the winding drops to a definite value, regardless of 80 variation in the pull of the shunt coil.

3. An electromagnetic switch comprising a switch member, a shunt coil for closing the same, an electromagnet energized by a variable current, a spring placed under strain 85 by the shunt coil in opposition to the pull of the electromagnet and means including said spring for preventing the closure of the switch member when the current in said winding is high and releasing the switch 90 member to permit it to be closed by the shunt coil when the current drops to a definite value.

4. An electromagnetic switch comprising a switch member, a shunt coil for closing the 95 same, and means controlled by a variable current for preventing closure of the switch member when the current is high and permitting it to be closed when the current drops to a definite value which is independent 100 of the pull of the shunt coil.

5. An electromagnetic switch comprising a switch member, a shunt coil for closing the same, electromagnetic means controlled by a variable current for preventing closure of 105 the switch member when the current is high and a spring opposing the electromagnetic means and acting to release the switch member when the current drops to a definite value so that it will be closed by the shunt 110 coil.

6. An electromagnetic switch comprising a switch member, a shunt coil for closing the same, electromagnetic means controlled by a variable current for preventing the closure 115 of the switch member when the current is high, a spring, said means including a movable element which places said spring under strain to oppose the electromagnetic means and acts to release the switch member when the current drops to a definite value so that it will be closed by the shunt coil.

7. An electromagnetic switch comprising a switch member, a shunt coil for closing the 125 same, an electromagnet energized by a variable current, means for preventing the closure of the switch member when the current is high, a spring held under tension by the magnet and means controlled by said spring 130

whereby when the current drops to a definite value a hammer blow is delivered which releases the switch member and permits it to be closed by the shunt coil.

8. An electromagnetic switch comprising a switch member, a shunt coil for closing the same, electromagnetic means controlled by a variable current for preventing closure of the switch member when the current is high, and a spring placed under strain by the shunt coil to oppose the electromagnetic means and acting to release the switch member when the current drops to a definite value and permit it to be closed by the shunt coil.

9. An electromagnetic switch comprising a switch member, a shunt coil for closing the same, a spring placed under strain by said coil, and means controlled by a variable current for preventing the closure of the switch member when the current is high comprising a magnetic winding carrying the variable

current, a movable mechanism held against the spring strain, said mechanism operating in response to the spring tension when the current drops to a definite value, and permitting said switch member to be closed by the shunt coil.

10. An electromagnetic switch comprising a switch member, an actuating winding connected to a source of substantially constant potential, a magnetic structure therefor for moving the switch member to closed position, a winding carrying a variable current and means whereby the switch member is normally locked in open position and is held in said position when the current in the latter winding is above a predetermined value and is closed by the potential coil when the current drops to said value regardless of variations in the pull of the potential coil.

It witness whereof, I have hereunto set my hand this 28th day of April, 1916.

EDWIN J. MURPHY.
